UNITED STATES PATENT OFFICE.

GEORGE W. CORBETT, OF SIOUX FALLS, SOUTH DAKOTA, ASSIGNOR TO NELS A. NELSON AND CORNELIUS O. WASTUN, BOTH OF SIOUX FALLS, SOUTH DAKOTA.

CONCRETE-COLUMN FORM.

1,374,063.

Specification of Letters Patent.

Patented Apr. 5, 1921.

Application filed June 4, 1920. Serial No. 386,587.

To all whom it may concern:

Be it known that I, GEORGE W. CORBETT, citizen of the United States, residing at Sioux Falls, in the county of Minnehaha 5 and State of South Dakota, have invented certain new and useful Improvements in Concrete-Column Forms, of which the following is a specification.

This invention relates to certain new and 10 useful improvements in concrete building forms, and relates particularly to forms used in concrete construction work.

The primary object of the invention is to provide a form which is constructed and assembled without the aid of bolts having nuts, and which can be adjusted to form posts of 15 different heights.

A further object of the invention is to provide a form of simple and economical 20 constructions which can be cheaply produced and easily and quickly assembled and knocked-down.

Other and further objects will be later set forth and of themselves manifested in the 25 course of the following description.

In the drawings:

Figure 1, is a side elevation of the invention;

Fig. 2, is a section on line 2—2 of Fig. 1; 30 Fig. 3, is a section on line 3—3 of Fig. 1;

Fig. 4, is a section on line 4—4 of Fig. 1;

Fig. 5, is a side elevation of a beam form for use where a beam is to be formed on the top of the column of post; and

35 Fig. 6, is a top plan view of Fig. 5.

In proceeding in accordance with the present invention, the form is constructed of a series of telescoping sections 1, each section being formed in two parts and having lateral abutting flanges 2, the free sides of the flanges being turned outwardly at right angles at 3, as depicted in Figs. 1, 2 and 3, thereby forming channels. For the purpose of holding the sections against spreading 45 movement angle bars 4, are employed having slotted bolts 5 secured thereto, the angle bars conformably engaging in the channels of the sections 1, and being shaped to brace against the latter so as to prevent bulging 50 upon pouring of the concrete or grout. Similar angle bars 6, are secured in the channels opposite to those in which the bars 4 are secured and have apertures through which the bolts 5, pass, the bolt slots receiving

wedges 7 which latter impinge against the angle bars 6, so that the latter act as wear plates for the wedges. The flanges 2 are slotted to receive the bolts 5 therethrough as depicted in Fig. 4.

For the purpose of holding the several sections in their telescoped relations, hinged clamps are employed composed of semi-circular sections 8, 8, hinged together at 9, and formed adjacent the hinged points with cut-outs 10, to receive the flanges 2 and 3. 60 The free or opposite ends of the sections 8, 8, are formed with straight edges 11, which abut the flanges 2, similar to straight edges 12, which abut the flanges 2, adjacent the hinged ends of the sections. The free ends 65 of the sections 8, are formed with outwardly projecting arms 13, having alined rows of perforations 14, through which tapered pins 15, are passed to engage slotted bars 16, which latter are received over the arms 13. 70 The outer sides of the arms 13 are inclined and relatively diverge toward the center of the form, so that the connecting bars can be wedged into engagement with the arms to tightly draw the clamp sections 8, into 75 engagement with the sections 1.

A top form of bell shape which also forms a pouring funnel is formed of sections 20, formed with flanges 2' and 3', similar to the flanges 2 and 3 of the sections 1, the sections 20, being held together by means of angle bars 4' and 6' and bolts 5' and wedges 7', as in the instance of the sections 1. The top form is also provided with a neck 21, which extends down into the uppermost section 1, 80 and with a circular horizontal flange 22, which seats on the uppermost section 1. Brackets 23, are attached to the section 1, and support the flange 22, of the top form and are secured to the latter by means of 85 bolts 24.

In cases where it is desired to form a beam integral with or attached to the top of the column, the form depicted in Figs. 5 and 6, is employed, the same embodying a circular, 100 body 30 split at 31, so as to be capable of insertion or telescoping in the top of the column form, and provided with flanges 31' and 32'. The beam form is inserted in the top section of the column form with its 105 flanges 31' received between the flanges 4 or 6 of the column form, and the angle bars of the flanges 4 or 6, are then secured to the

flanges 31' of the beam form as disclosed in connection with the column form. The bell-shape form of top can be used with the top of the column form by insertion therein if desired.

The parts can be thus easily and quickly knocked-down and compactly nested for shipment or storage, due to the two part nesting formation of the sections. Further, 10 the sections 1 can be adjusted vertically and secured by the hinged clamps to obtain columns of varying heights.

What is claimed is:

1. In a concrete form, telescopic sections, 15 each consisting of two mating parts, each part having an outwardly extending flange at each side thereof, the outer sides of the flanges being turned outwardly at right angles to form channels, angle bars in the 20 channels abutting the sections to brace the latter, slotted bolts extending through the angle bars and flanges, wedges extending through the slots of the bolts and impinging against the adjacent angle bars, clamps consisting of hinged sections having parts received in the channels and having tapered arms at their free sides, slotted bars wedged over the tapered arms, said arms having rows of perforations, and tapered pins engaged 25 through the perforations and abutting the slotted bars to hold the latter in place.

2. In a concrete form, telescopic sections, 30 each consisting of two mating parts, each part having an outwardly extending flange at each side thereof, the outer sides of the flanges being turned outwardly at right angles to form channels, angle bars in the 35 channels abutting the sections to brace the latter, slotted bolts extending through the angle bars and flanges, wedges extending through the slots of the bolts and impinging

against the adjacent angle bars, clamps consisting of hinged sections having parts received in the channels and having tapered arms at their free sides, slotted bars wedged over the tapered arms, and means to hold the slotted arms in adjusted position on the arms. 45

3. In a concrete form, telescopic sections, 50 each consisting of two mating parts, clamps consisting of hinged sections engaged around the mating parts and having arms at their free sides, one of the arms having a tapered part, a device engaged with both of the arms and having a part received over and wedged into engagement with said tapered part, and means to hold said device in its said wedged engagement with the tapered part. 55

4. In a concrete form, telescopic sections, 60 each consisting of two mating parts, each having an outwardly extending flange at each side thereof, clamps consisting of hinged sections having parts abutting said flanges and having tapered arms at their 65 free sides, slotted bars wedged over the tapered arms, said arms having rows of perforations, and tapered pins engaged through the perforations and abutting the slotted bars to hold the latter in place. 70

5. In a concrete form, telescopic sections, 75 each consisting of two mating parts, clamps consisting of hinged sections engaged around the mating parts and having arms at their free sides which arms have tapered outer parts which converge outwardly of the form, slotted bars wedged over the tapered parts and having the outer end walls formed by the slots directly engaged with the tapered outer parts, and means to hold 80 the bars in wedged engagement with said tapered parts.

In testimony whereof I affix my signature.
GEORGE W. CORBETT.
